WORKMAN'S WARNING SYSTEM FOR
RAILWAYS

Patsy Addorisio, Portchester, N. Y.

Application April 10, 1948, Serial No. 20,172

2 Claims. (Cl. 246—124)

1

This invention relates to a warning signalling system, and more particularly to a signalling system for railways to provide at desired points along the railbed a warning of an approaching train, so that construction or maintenance men working on the roadbed, rails or other equipment in the vicinity of such points will be given ample warning of the approaching train.

It is an object of this invention to provide a warning system under the control of the workmen which will give the workmen ample warning of an approaching train and enable them to get out of the path of the train.

Other objects and advantages will be apparent from the following detailed description thereof taken in connection with the accompanying drawings in which

Figure 1 is a diagrammatic view of a portion of the railway showing the usual power line carrying poles spaced along the roadbed and showing a preferred arrangement of certain parts of the warning system of this invention on these poles and along the roadbed; and

Figure 2 is a wiring diagram of a warning system embodying this invention.

Referring to the drawing the warning circuit is illustratively shown as applied to successive divisions A and B of a railroad, it being understood that the railroad is divided into a large number of such divisions, the exact number depending on the length of the railroad. Each division may be of any desired length, say two miles, or longer. As the component parts of the warning circuit in each division are identical, only the parts associated with division B will be described in detail below, identical parts in division A being given the same reference numerals primed.

A main power source P comprises a pair of power lines 11 and 12 supported by poles 13 spaced at intervals along the length of the railroad. At the beginning of each division is a warning light 14, which, as shown in Figure 1, is mounted on one of the poles 13, but which may be suspended above the tracks 10 or otherwise mounted so as to be clearly visible to an approaching train. A normally open double-pole, single-throw switch 15 is positioned at the beginning of each division near the tracks 10. Switch 15 in each division is momentarily closed by a suitable actuator arm (not shown) carried by the locomotive or first car of each train as the latter passes the switch 15, the switch springing open under the action of a spring or other suitable means once the actuator arm is no longer in contact therewith.

2

Each division A, B, etc., is provided with a plurality of switches 16, 17 spaced along the roadbed where they are readily accessible to the workmen. The switch 16 in each division is located near the beginning of the division and is of the double-pole, single-throw type having sections a and b. The switches 17 in each division are located at spaced points along the roadbed and are of the single-pole, single-throw type, as indicated diagrammatically in Figure 2.

Three switches 16, 17 are illustratively shown in each division A and B in Figure 2. These switches, as shown in Figure 1, are mounted on the poles 13 where they are readily accessible to the workmen. However, it will be understood that any desired number of switches 17 could be spaced along the roadbed at any convenient location where they are accessible to the workmen.

Section b of switch 16 and switches 17 of division B are connected in parallel, lead 18 connecting the movable contact arms and lead 19 connecting the fixed contacts of the switches 17 and of section b of switch 16. Section a of switch 16 of division B is connected in parallel with section b' of switch 16' of division A and with switches 17' of the preceding division A by leads 18' and 19'. Thus section a of each switch 16 is connected in parallel with section b' of a switch 16' in the preceding division and section b of each switch 16 is connected in parallel with section a of a like switch in a succeeding division of the railroad.

Lead 18 is connected by lead 21 to power line 12 and lead 19 is connected by lead 22 to one side of warning lamp 14, the other side of which is connected by lead 23 to power line 11. Lead 22 is also connected by lead 24 to one of the fixed contacts 25 and to one of the movable contact arms 26 of switch 15. A fixed contact 27 of switch 15 associated with movable contact arm 26 is connected by a lead 28 to a terminal 29 on terminal strip 31. A plurality of terminal strips 31 is provided in each division spaced along the roadbed; one of these is illustratively shown in each division in Figure 1, but it will be understood, as above indicated, a number of these strips are positioned at suitable points along the length of each division, desirably one such strip is provided for each switch 16 and 17. The remaining terminals 32 and 33 on terminal strips 31 are connected, respectively, to power lines 12 and 11 by leads 34 and 35.

Movable contact arm 36 of switch 15 associated with fixed contact 25 is connected by a lead 37 to a fixed contact 27 of the switch 15 in the succeeding division (not shown). Fixed contact 27 of switch 16, shown in Figure 2, is connected

by a lead 38 to the movable contact arm 36' of switch 15'.

A portable alarm 39 is provided comprising a normally open relay R of the double-pole, single-throw type having a common movable contact arm 41, a pair of fixed contacts 42 and 43 associated therewith, an alarm bell 44, a normally closed manually operable switch 45 and a terminal strip 46 provided with terminals 47, 48 and 49 thereon. Terminal 47 is connected by lead 51 to one side of the coil 52 of the relay R and to fixed contact 42. The other side of the coil 52 is connected by lead 54 to one side of the switch 45, the other side of which is connected by lead 53 to terminal 49 and by lead 55 to one side of alarm bell 44. The other side of bell 44 is connected by lead 56 to fixed contact 43. Movable contact arm 41 is connected by lead 57 to terminal 48 to complete the circuit.

Operation

When repairs are to be made along the roadbed one of the workmen of the crew first connects his portable alarm box 39 to a terminal strip 31 disposed on a pole near the place where the crew will work, the switch 45 in the portable alarm being closed. Thus terminals 29, 47; 32, 48 and 33, 49, respectively, are connected. Assuming that the workman is near the beginning of a division B, he will then close switch 16. Section b of switch 16 will complete a circuit to warning light 14 from power line 12, leads 21, 18, through closed section b of switch 16, lead 22, lamp 14, lead 23, to powerline 11 thereby energizing the lamp 14. As section a of switch 16 will also be closed a circuit will be completed to lamp 14' of division A from power line 12, leads 21' and 18' through closed section a of switch 16 in division B, leads 19' and 22' through lamp 14' and lead 23' to power line 11, thereby energizing lamp 14'. Thus, as a train enters division A the engineer will see the signal light 14' and have ample time to slow down before entering division B where the workmen are located. As the train enters division A its actuator arm will momentarily close switch 15'. This will complete a circuit to portable alarm 39 in division B to energize the latter. This circuit is from main 12, leads 21', 18' through closed section a of switch 16 in division B, leads 19', 22' and 24', fixed contacts 25' and movable contact arm 36' of switch 15', which are in engagement, lead 38 to fixed contact 27 of switch 15 of division B, lead 28 to terminal 29 on terminal strip 31 thence to terminal 47 of alarm box 39, lead 51 to relay coil 52, through the relay coil lead 54, closed switch 45 and lead 53 to terminal 49, thence to terminal 33 on terminal strip 31 and lead 35 to power line 11.

Energization of relay coil 52 will bring movable contact arm 41 into engagement with fixed contacts 42 and 43 and complete a holding circuit for coil 52. The circuit is as follows—from line 12, lead 34, terminal 32, terminal 48, lead 57, movable contact arm 41, which is in engagement with fixed contacts 42 and 43, coil 52 lead 54, closed switch 45 and lead 53 to terminal 49 and terminal 33 through lead 35 to line 11. Thus, as the train passes switch 15' in division A and the switch opens, coil 52 will remain energized. As bell 44 is now in circuit being in parallel with relay coil 52, the bell will ring. The circuit for the bell is from line 12, lead 34, terminals 32 and 48, lead 57, movable contact arm 41, fixed contact 43, lead 56 through bell 44, leads 55 and

53 to terminals 49 and 33, then through lead 35 to line 11.

Thus ample warning will be given to the workmen at the beginning of division B of the approach of the train. Since no portable alarm is connected to a terminal strip 31' in division A no alarm will be sounded in this division.

As the train enters division B the actuator arm thereof will momentarily close switch 15. As alarm bell 44 is already ringing the closing of switch 15 will have no effect.

Should a workman also be working in division A his alarm will be energized as well as the alarm in division B. However, as there is no need for his alarm bell to be again actuated after the train passes him, switch 15 is so connected that the passage of a train will not actuate the alarm bell in the preceding division. Thus, as movable contact arm 26 and fixed contact 27 are brought into engagement by the passage of a train, no flow of current to the coil of relay R' in division A takes place because contact arm 36' is not in engagement with the fixed contact 29'.

After the train has passed the workman in division B need only open switch 45 in the alarm box 39 to break the holding circuit to relay coil 52, thereby deenergizing the latter and separating movable contact arm 41 and fixed contacts 42, 43. This will break the circuit to alarm bell 44. The workman then again closes switch 45 to place the system in readiness for the next train.

When the job is finished the workman need only remove the alarm box and open switch 16 to deenergize the lamps 14 and 14'.

Should a workman be working at a point remote from switch 16 in division B he connects his alarm box, as above described, with a terminal strip near his place of work, closes switch 45 and a switch 17 also near the place of work. The closing of switch 17 will energize lamp 14 but not lamp 14', since switch 16 is open. As the train approaches lamp 14 it slows down in view of the signal and in passing switch 15 momentarily closes the switch energizing bell 44, as hereinabove described, giving the workmen ample time to get out of the path of the train.

It will be noted this invention provides a warning system under the control of the workmen, which system is so designed that should the workmen be working close to the beginning of a division, signals are energized at the beginning of the division in which the workmen are located, as well as in a preceding division, the approaching train entering the preceding division automatically energizing an alarm where the workmen are positioned giving the workmen ample time to get out of the path of the train. Should the workmen be working in a portion of the division remote from its beginning then only the signal at the beginning of this particular division is energized and the train automatically operates the alarm only when it enters this particular division.

Since different embodiments of the invention could be made without departing from the scope of this invention, it is intended that all matter contained in the above description or shown in the accompanying drawing shall be interpreted as illustrative and not in a limiting sense.

70 What is claimed is:

1. In a warning system for a railway consisting of a plurality of successive divisions, in combination, a visible signal at the beginning of each division, a single-throw train operated switch at the beginning of each division, which switch

is normally open and is adapted to be momentarily closed by a passing train, a double-pole, two-section switch located at the beginning of each division, one section of each double-pole, two-section switch being in circuit with a section of a like switch in a preceding division and the other section of said double-pole, two-section switch being in circuit with a section of a like switch in a succeeding division, a plurality of individual switches located in spaced relationship along the length of each division and connected in parallel with each other and with the said double-pole, two-section switch in said division, a pair of power lines in each division in circuit with (1) said visible signal, (2) said train-operated switch, (3) one section of said double-pole, two-section switch, and (4) said plurality of said individual switches in said division, closing of any of said individual switches in a division energizing the visible signal in that division and closing of said double-pole, two-section switch in a division energizing the visible signal in that division and also in a preceding division, a series of terminal strips disposed in spaced relationship in each division, and a portable alarm adapted to be connected with the terminal strip, said alarm adapted to be energized by the closing of the train operated switch by a passing train in the division in which said alarm is located and the closing of one of said individual switches or the double-pole, two-section switch in said division in which said alarm is located.

2. In a warning system for a railway consisting of a plurality of successive divisions, in combination, a visible electric signalling device at the beginning of each division, a single-throw train operated switch at the beginning of each division, which switch is normally open and is adapted to be momentarily closed by a passing train, a double-pole, two-section switch located at the beginning of each division, each section having a fixed contact and a movable arm, one

section of each double-pole, two-section switch being in circuit with a section of a like switch in a preceding division and the other section of said double-pole, two-section switch being in circuit with a section of a like switch in a succeeding division, a plurality of individual switches located in spaced relationship along the length of each division and connected in parallel with each other and with said last-named section of said double-pole, two-section switch in said last-named division, a pair of power lines in each division, a series connection between said visible signalling device, said power lines and said last-named section of said double-pole, two-section switch, whereby closing of any of said individual switches in a division energizes the signalling device in that division and closing of said double-pole, two-section switch in a division energizes the signalling device in that division and also in a preceding division, a series of terminal strips disposed in spaced relationship in each division, and a portable alarm adapted to be connected with one of said terminal strips and be energized by the closing of the train operated switch by a passing train in the division in which said alarm is located, and the closing of one of said individual switches or the double-pole, two-section switch in said division.
